C. D. FAHRNEY.
ASH CAN STAIR DEVICE.
FILED APR. 11, 1922.

FIG. 1.

FIG. 2.

FIG. 3.

FIG. 4.

Inventor:
C. D. Fahrney

UNITED STATES PATENT OFFICE.

CALLO D. FAHRNEY, OF CAMBRIDGE, MASSACHUSETTS.

ASH-CAN STAIR DEVICE.

Application filed April 11, 1922. Serial No. 551,543.

To all whom it may concern:

Be it known that I, CALLO D. FAHRNEY, a citizen of the United States, residing at Number Twenty-six Ellery Street, in the 5 city of Cambridge, in the county of Middlesex and State of Massachusetts, have invented a new and useful Ash-Can Stair Device, of which the following is a specification.

10 My invention consists of a simple device and has for its object to enable a person to move filled ash barrels or other heavy objects up an ordinary stairs with comparative ease.

15 Referring to the accompanying drawings, Figure 1 is a perspective showing the device in position on an ordinary stairs.

Figure 2 is a front or top view showing the device in an operative position on the 20 stairs.

Figure 3 is a view intended to show how the device, in the form as here applied, may be converted into an ordinary carrying hand truck while not employed for stair ascending purposes.

Figure 4 shows a modified form.

Like letters refer to like parts in the different views.

The device illustrated consists of a 30 handled frame of rigid construction adapted to receive and retain the ash can or other object being transported, supplied with wheels and provided with what I shall term herein pivoted supports, indicated respectively by 4 and 5 and attached to the axles.

In the adaptation of my invention as here shown the pivoted supports, 4 and 5, are free at one end and extend beyond the limit of the wheels. With the device in

40 position on the stairs, as shown in Fig. 1, these supports gravitate against the steps and will catch thereon and support the load on either or both sides as the apparatus is moved upwardly and forwardly by the operator.

45 In operation the handles are seized and with the wheels bearing against the next step above the operator lifts on the handle to his right raising the load on that side while it is supported by the wheel on the opposite side.

50 The pivoted support 4 is shown notched and when that side of the device is raised the shoulder of the first notch is available for retention and supporting purposes, this shoulder being designated by 6, Fig. 1.

55 With the load thus supported on one side

by the support the operator may next lift on the handle to his left, bringing the other support into play. At this stage both wheels will be free from the step below but will remain pressed against the edge of the step above by reason of the leaning position of the supports. Then the operator again lifts the side to his right until the next shoulder 7 becomes operative for retention purposes. The pivoted supports may be of 60 any practicable length and provided with as many notches as desired. It is obvious that the device and its load may in the foregoing manner be negotiated upward to a point where the wheels will roll onto the next step 65 above, when the operation is repeated until the top is reached.

In Fig. 2 the device is shown resting on two steps, one side being supported by the wheel on one step while the other side rests 70 on the pivoted support 4 standing on the step below. In practice it is not found necessary to have the supports long enough to elevate the bottom of the wheel to the level of the step above as the operator can easily 75 draw the wheels onto the step after being well onto the edge of the same.

In practice I provide the pivoted supports with staggered notches or shoulders and as the handled end of the frame is 80 manipulated from side to side by the operator the pivoted supports act as a fulcrum also and in order that the load may be tilted on the supports without sliding the adjacent wheel sideways against the step above I 85 provide sufficient play between the frame and wheel to permit of a rocking movement without any such result, this feature being well illustrated by Fig. 2.

The foregoing describes the method of 90 negotiating the device and load from one step to another. In ascending the first step the pivoted supports function on the floor, the shorter of the two first and produce 95 equally satisfactory results.

In practice the pivoted supports may be attached to other points than the axles of the wheels and in fact the stair ascending purpose of my invention may be accomplished with elements other than wheels 100 adapted to serve the same or similar purposes on the stairs and I do not wish to be limited to the construction shown but in practice I combine the stair ascending feature with a conveyance adapted for ordinary 105

use and for conveying cans down stairs. Therefore in the device illustrated I provide means for converting the device into a handy truck or conveyance by enabling the operator to throw the pivoted supports into and out of the way position except when needed for stair climbing purposes. For this purpose I provide the retaining hooks 8 and 9 which are attached to the frame. A projection, as illustrated by 10, Figs. 1 and 3, may be provided on the pivoted end of the supports which will enable the operator with the toe of his shoe to throw the supports over into the hooks 8 and 9, leaving them in position illustrated in Fig. 3, this method of manipulating the supports with the foot being exceedingly advantageous when the operator has a filled can on the truck.

20   Claims:

1. An ash can stair device comprising load retaining body having hand holds, ground supporting means and provided with pivoted supports oppositely attached thereto with their free ends extending beyond the point of ground rest and adapted to catch on the stairs and sustain the load on one side while the other side is being moved upwardly and forwardly by the operator, substantially as and for the purposes set forth.
2. An ash can stair device comprising load retaining body adapted to rest on the stairs and having pivoted supports oppositely attached thereto with retaining shoulders on their under sides adapted to catch on the steps to retain the load on one side while the other is being moved upwardly

and forwardly by the operator, substantially as and for the purposes set forth.

3. An ash can stair device comprising load retaining body adapted to rest on the stairs and provided with supports pivotally attached thereto opposite each other with notches in their under side adapted to 45 catch on the steps and sustain one side of the device while the other is being moved upwardly and forwardly by the operator.

4. An ash barrel truck having supports pivotally attached to the axles with their free ends extending beyond the rims of the wheels and adapted to catch on the steps and sustain the load on one side while the other is being moved forward by the operator.

5. A stair ascending device comprising hand controlled load retaining body adapted to bear and move on the stairs and provided on its under side with oppositely arranged detents pivotally attached thereto and 60 adapted to catch on the steps alternately to prevent one side from slipping back while the other is moved upwardly and forwardly by the operator.

6. A stair ascending device comprising 65 handled load retaining body adapted to move on the stairs and provided on its under side with oppositely positioned detents attached thereto and adapted to catch on the steps alternately to sustain the load 70 on one side while the other is moved upwardly and forwardly by the operator.

CALLO D. FAHRNEY.
